UNITED STATES PATENT OFFICE

135,858

DESIGN FOR A GRATE

Richard M. O'Brien, Arlington Heights, Ill.

Application September 11, 1942, Serial No. 108,185

Term of patent 14 years

To all whom it may concern:

Be it known that I, Richard M. O'Brien, a citizen of the United States, residing at Arlington Heights, in the county of Cook and State of Illinois, have invented a new, original, and ornamental Design for a Grate, of which the following is a specification, reference being had to the accompanying drawing, forming a part thereof.

In the drawing:

Figure 1 is a perspective view of a grate showing my new design; and

Figure 2 is an end elevational view thereof.

The dominant features of the design reside in the portions shown in full lines.

I claim:

The ornamental design for a grate, substantially as shown and described.

RICHARD M. O'BRIEN.
